UNITED STATES PATENT OFFICE

LOYAL GRANT ROBBERTS, OF SANTA MONICA, CALIFORNIA

MULTICURTAIN ADVERTISING APPARATUS

Application filed June 24, 1929. Serial No. 373,224.

This invention relates to advertising apparatus and especially to that type incorporating display curtains.

An object of this invention is to provide a simple, practicable and efficient apparatus for the display of a large number of individual advertisements either in a continuous motion or in intermittent stop periods.

A further object is to provide a machine of compact structure in which a number of endless display curtains are closely installed and provide for large capacity of various display panels without using a large base area or chamber space.

Other objects, advantages and features of construction and combination, and mode of operation will be made manifest in the ensuing description of the herewith illustrative embodiment; it being understood that modifications, variations and adaptations may be resorted to within the spirit, scope and principle of the invention as it is more directly claimed hereinafter.

Figure 1 is a front elevation of the apparatus.

Figure 2 is a vertical, central section from front to rear of the apparatus.

Figure 3 is a detail of the driving drum of the mechanism.

Figure 4 is a vertical section from side to side, showing the display curtains and driving means in detail.

Figure 5 is a vertical section on line 5—5 of Fig. 4, showing arrangement of superdis-

posed curtains of the apparatus.

Figure 6 is a detail of connected ends of a display curtain.

The present machine is incorporated in a suitable housing or cabinet 2 having movable side wall doors 3 whereby to provide access to the mechanism and enable ready change of advertisement belts from time to time. The rear of the cabinet has doors 4.

A feature of this invention is the effective driving of a plurality of endless curtains from a single drive belt 5 which passes over a top roller 6 and a bottom roller 7 disposed horizontally just in rear of the windowed front 8 of the cabinet. From the bottom roller 7 the belt passes up to a driving drum

10 and forms a sag bight 11 in which is disposed a gravity or tension roller 12 from which the belt passes up to a supplemental drum 13.

The belt 5 is pressed onto the drum 13 by a presser roller 14 from which it passes up to the top roller 6, thus completing the circuit.

The main drum 10 is constantly driven through a reduction train 15, by a suitable motor 16.

In some cases it may be desired to drive the belt 5 intermittently and to that end the drum shaft 10', or the drum, is provided with cams 17 operative to engage arms of a yoke 18 pivoted at 19 and having links 20 in which the tension roller 12 is carried. When the cams 17 act to lift the roller 12 lack of friction causes the drum 10 to revolve without moving the belt which dwells until the cams again release the yoke and lower the roller 12 to tensioning position in belt bight 11.

In the present disclosure the front 8 has a central window A and flanking windows B—B', and C—C'.

The belt 5 is about as wide as the window A and on it is draped an endless curtain 20 which is about as wide as window A and loops in front of rollers 6—7 and lies close to the front 8 and passes back of the drum 10. The weight of the central curtain 20 causes it to travel with its supporting belt 5 as this is driven.

The top roller 6 is secured on its shaft 6' and to the ends of this are applied extension rollers 6^b and 6^c which carry draped endless curtains 20^b and 20^c registering with the windows B and C. The lower bights of the curtains 20^b—20^c are deflected rearward in the cabinet and carry tension rollers 20' to keep them taut on their drive drums or rollers.

The supplemental drum 13 is secured on shaft 13' and to the ends of this are applied extension drums 13^b and 13^c on which hang endless curtains 21^b and 21^c which register with windows B'—C' and lie in front of the lower bights of the curtains 20^b—20^c. The curtains 21^b—21^c have tension rollers 22. The front planes of all the curtains are substantially coplanar and lie close to the front windows so that panels X of advertis-

ing media are clearly visible, in succession during operation of the machine.

It will be seen that the belt 5 drives the shafts 6' and 13' and these drive the drums carrying the lateral curtains 20^b, 20^c, 21^b and 21^c. To change the lateral curtains it is only necessary to slide them edgewise off their drive rollers. The central curtains 20 may have separable meeting ends attached by any suitable fastening, Fig. 6. The display part 10 of the curtains 20^b—20^c are relatively superimposed as is clearly seen in Fig. 5; the upper curtains deflecting back over guides 28—29 to clear the drums 13^b—13^c.

What is claimed is:

1. In an advertising apparatus, a windowed front wall, a system of display curtains with portions in a common plane at said front to be seen through the windows, a drive belt on which one of the curtains is suspended to be driven, and supplemental drive drums carrying respective curtains of the system and driven by said belt.

2. In an advertising apparatus, a windowed front wall, a system of display curtains with portions in a common plane at said front to be seen through the windows, a drive belt on which one of the curtains is suspended to be driven, and supplemental drive drums carrying respective curtains of the system and driven by said belt, and means for effecting an intermittent dwell of the drive belt.

3. In an advertising apparatus, a windowed wall and a system of endless display curtains exhibitive at the windows concurrently, an endless driven belt carrying one of the curtains, and extension drums driven by said belt and carrying the remaining curtains.

4. In an advertising apparatus, a windowed wall and a system of endless display curtains exhibitive at the windows concurrently, an endless driven belt carrying one of the curtains, and extension drums driven by said belt and carrying the remaining curtains, and tension means for the belt to secure friction of the belt on the driven drums.

5. In an advertising apparatus, a windowed wall and a system of endless display curtains exhibitive at the windows concurrently, an endless driven belt carrying one of the curtains, and extension drums driven by said belt and carrying the remaining curtains, and tension means for the belt to secure friction of the belt on the driven drums, and means to intermittently act on said tension means to cause it to dwell intermittently.

6. In an advertising apparatus, a top roller and a bottom roller and a driven drum, a drive belt running from roller to roller and having a bight around said drum, a tensioning roller for the belt, a supplemental drum driven by the belt and having exten-

sion roller drums, said top roller having extension drums, and a system of endless display curtains one of which is carried by the belt and the others by respective extension drums.

7. In an advertising apparatus, a top roller having extension drums at its ends and display curtains suspended from the drums, a main driving drum, a belt rove on said top roller and main drum to drive the former, and a supplemental drum driven by the belt and having extension ends, and endless display curtains respectively operated by the said belt and said extension drums concurrently.
